UNITED STATES PATENT OFFICE.

HARRY MASON, OF DENVER, COLORADO.

STARTER FOR AUTOMOBILE-ENGINES.

1,000,929.

Specification of Letters Patent. Patented Aug. 15, 1911.

Application filed August 31, 1909. Serial No. 515,469.

To all whom it may concern:

Be it known that I, HARRY MASON, a citizen of the United States of America, residing in the city and county of Denver and 5 State of Colorado, have invented a new and useful Starter for Automobile-Engines, of which the following is a specification.

This invention relates to starting devices for automobile engines.

10 The object of the invention is to provide a starting device of this character, which is adapted to obviate the necessity of first cranking the machine, and to this end I provide means for delivering charges of a suitable explosive mixture to the engine, comprising a four-way valved distributor connected by pipes with the several engines, and means for delivering said mixture under pressure to said distributor, the valves of 15 which are operated by a cam connected with the operating shaft of a rotary timer, which is connected with the cam shaft of the engines, the opening of the valves of said distributor being so timed relatively to the timer, that immediately before said timer closes a circuit between the battery and the spark plug of an engine, the valve connecting the distributor with said engine is 20 opened, permitting a charge of the explosive mixture to be delivered to the engine.

25 A further object of the invention is to provide a suitable clutch connection between the valve-operating cam and the timer shaft, and means for disengaging said clutch, when the timer is turned to advance the spark under the increasing speed of the engine, whereby the valves are rendered inoperative.

30 These objects are obtained by the mechanism illustrated in the accompanying drawings, in which:

Figure 1, is a plan view illustrating the front portion of an automobile and the application of the improved starting device thereto. Fig. 2, is an elevation of the dash board, showing the arrangement of the parts constituting the invention. Fig. 3, is a horizontal sectional view through the valved explosive mixture-distributer. Fig. 4, is a vertical sectional view through the distributor and timer, showing a clutch mechanism for connecting the valve-operating rotary cam and timer, and means for disconnecting the clutches. Fig. 5, is a side elevation of the valve, showing one of the track cams thereon, which are engaged by 45 wheels, carried by the timer, whereby the

valve is lifted to disengage the clutches, when the timer is turned. Fig. 6, is a side elevation of the clutch secured upon the shaft of the rotary valve cam. Fig. 7, is a side elevation of the clutch carried by the timer shaft. Figs. 8 and 9 are plan views respectively of the two clutch members. Fig. 10, is a side elevation showing the two clutch members in position to engage. Fig. 11, is a similar view showing the clutch members in engagement. Fig. 12, is a horizontal, sectional view through the sight feed cap for the explosive mixture. Fig. 13, is a vertical, sectional view through the same. Fig. 14, is a side elevation, partly in section, illustrating the outlet valve connected with the storage tank. Fig. 15, is a plan view of the cam-turning knob. Fig. 16, is a horizontal sectional view through the timer, and Fig. 17 is a diagrammatic view illustrating the operation of the improved starter.

Similar letters of reference refer to similar parts throughout the several views.

Referring to the accompanying drawings, 30 the numeral 1, designates the frame of an automobile; 2, the radiator; 3, the engine casings; 4, the crank shaft; 5, the fly wheel; and 6, the cam shaft; all of these parts being of a type now in general use.

To one side of the frame 1, is hinged a yoke-shaped frame 7, which extends over and above the fly wheel 5, and at the forward end of this frame is journaled a shaft 8, carrying a friction wheel 9, adapted to 90 contact with the said fly wheel. A pinion 10 is also secured upon the friction wheel shaft, which meshes with a gear wheel 11, secured to a stub shaft 12, journaled upon one side of the frame 7, and to the gear 95 wheel 11, is pivotally secured the forward end of the piston rod 13, of an air compressing cylinder 14, which is of a style in common use, and therefore requires no further illustration or description. A pipe 100 15, extends from the rear end of the cylinder 14, and preferably connects with a tube 16, forming an extension of one of the journals of the said cylinder, and a pipe 17 connects this tube with a storage tank 18. The pipe 105 15 has an ordinary check valve 19, which prevents back pressure in the cylinder 14. A pipe 20 extends from the rear end of the storage tank to a pressure gage 21, on the dash board, and a pipe 22 extends from said tank to a sight feed cup 23, also secured to the dash board. The sight feed cup com-

prises a glass cylinder of suitable size, which is closed at top and bottom by caps 24 and 25 respectively. The pipe 22 enters the cup through the bottom cap, and extends to 5 within a short distance of the top of the cup. A supply pipe 26 extends from the bottom of the cup to a supply tank 27, which is adapted to hold a suitable explosive mixture, and this mixture may feed by gravity 10 to the cup 23, or when it is impossible to place the tank in such a position that the mixture will feed by gravity, the same may be forced out by air under pressure. A tube 28 extends from the top cap 24 to 15 which it is secured, through the bottom cap 25. The lower end of the tube is threaded and a nut 29 is screwed thereon, against the bottom cap, thus clamping the parts of the cup together. The nut 29 has a threaded 20 extension, to which a union 30 is screwed, which couples thereto a pipe 31, the opposite end of which is connected to a four-way distributor 32, which will presently be fully described. An aperture 33 is formed 25 in the tube 28, near its upper end, and a tube 34 is secured in any suitable manner, to the cap 24, so as to surround the tube 28, and extends to within a slight distance of the bottom of the cup. A space of suitable 30 width is left between the tubes 28 and 34, and a small vent hole 35 is formed in the tube 34, near its upper end.

The supply pipe 26 has a cut-off valve 36, which is opened to admit a charge of the 35 explosive mixture to the sight feed cup, and the pipe 22 connecting the said cup with the air storage tank, is provided with a valve 37, having an upright operating stem 38, which extends up through the floor of the machine 40 in position to be pressed by the foot of the attendant, and when this stem is pressed, the valve 37 is opened and air under pressure is admitted to the sight feed cup through the pipe 22, forcing the charge of 45 explosive mixture therein, up through the outside tube 34, through the aperture 33, and into the tube 28, whence it passes through the pipe 31 to the distributor. The vent hole 35, at the top of the tube 34, permits the escape of the air when the explosive 50 mixture is rising in the cup, whereas if the vent were not present the mixture would be prevented from rising in the sight feed cup, and would thus interfere with the filling of 55 the cup.

The distributor 32 comprises a cylindrical casing or receptacle, having four equi-distant threaded holes through its periphery, in which are screwed nipples 39, the inner 60 ends of which form seats for valves 40, 40^a, 40^b, and 40^c, which are substantially of bell crank shape, and are each centrally pivoted between a pair of ears 41, formed on the interior of the distributor. These valves are 65 normally held against their seats by suit-

able springs 42, and their free ends are in position to be engaged successively by a rotary cam 43, having a depending hollow stem 44, which extends through a hub 45 in the bottom of the distributor. The operating face of the cam is of such length that before escaping the end of one valve, it engages and opens the next succeeding valve, the purpose of which will be explained hereinafter. Thus one outlet from the distributor is always open. To the nipples 39 are connected, in any suitable manner, pipes 46, 47, 48, and 49, which connect respectively with the engines A, B, C, and D, communication between the engines and the distributor being effected by the engagement of the cam 43, with the tails of the valves, whereby they are rocked on their pivots and thus moved away from their seats. The pipes are provided, adjacent to the engines, 85 with check valves X. A stuffing box 50 is screwed upon the end of the hub 45, and upon the end of the stem 44, which projects through this box, is rigidly screwed a disk 51, from the under side of which projects two pins 52 and 53 of unequal length, which are adapted to extend into a recess 54, in the edge of a similar disk 55, which is rigidly secured upon the shaft 56, of a timer 57, which is of a type in common use, 95 and comprises a fiber ring 58, having four equi-distant contacts 58^a, from which screws 59 extend out through the ring, and are provided with wire clamping nuts 60. Upper and lower plates 61 and 62 respectively, inclose the ring, and a hub 63 is secured to the shaft 56, having a bifurcated arm 64 in which is pivotally mounted a spring actuated arm 65, carrying a contact roller 66 at one end, which successively engages the contacts 58^a as the shaft 56 rotates. A sleeve 67 extends into a hub 68 in the bottom plate of the timer, and the shaft 56 extends loosely through this sleeve, and upon its lower end is secured a bevel gear 69, which meshes with a bevel gear 70, of the same diameter, which is secured upon the rear end of the cam shaft 6 of the engines, and while I have illustrated a type of engine in which the intake valves are located on one side and the exhaust valve on the other, thus requiring two cam shafts, it is apparent that the result is just the same when the device is connected to engines having all the valves on one side, and consequently but a single cam shaft. As the gears 69 and 70 are of the same diameter, the speed of the timer shaft is identical with that of the cam shaft, and the timer is so timed relatively to the cam shaft, that it closes a circuit through the battery, or magneto, as the case may be, and the spark plug of each engine, at the instant the engine is ready to be fired.

Upon opposite sides of the bottom of the

distributer 32 are secured cam tracks 71, which are of the form shown in Fig. 5, and these tracks rest upon rollers 72, mounted in the bifurcated ends of posts 73, which 5 are secured to the timer by screws 74, which pass through the same and into the said posts. When the rollers engage the ends 75 of the tracks, the distributer 32 is in its lowest position, the clutch disks 51 and 55 10 are in engagement, and the cam 43 is turned in unison with the timer shaft, but when the timer is turned to advance the spark, as the engines gain speed, the rollers 72 ride under the cam portions of the tracks, and 15 lift the distributer so that the disk 51 is lifted out of engagement with the disk 55, and the cam and valves are rendered inoperative. When the distributer is lowered again for the purpose of starting the engines, the longer pin 53 of the clutch disk 20 51 first engages the face of the disk 55, the disk 51 is then turned manually in a backward direction, and as the pin 53 passes the adjacent end of the recess 54 of the 25 disk 55, the disk 51 drops until the shorter pin 52 strikes the face of the disk 55, as shown in Fig. 10, and the pin 53 extends partially into the recess 54, in position to be engaged by the opposite end of the said 30 recess, and as the disk 51 is still further turned the short pin 52 drops into the recess 54, and at the same time the pin 53 is engaged by the adjacent end of the said recess, and the two disks are locked in engagement 35 with each other. This arrangement provides a clutch for positively and quickly locking the disks together as the unequal length of said pins makes it impossible for them to pass the recess 54, without the 40 longer pin being engaged by the end of said recess.

The cam 43 and disk 51 are turned manually by a rod 76, which is rigidly secured to the cam 43, and extends out through the 45 top of the distributer. The upper end of the rod is provided with a knob or disk 77, for turning the cam and disk 51, and this knob is preferably provided with four indicating marks or notches 78, at equi-distant points 50 around its circumferential edge, which may be numbered in the same relative order in which the engines are fired, and these indicating marks register with a pointer 79 secured to the dash board. In this way, when 55 the disk 51 is locked to the disk 55, the knob 77 will always indicate the engine that is to be fired, as the timer shaft carrying the disk 55 has the same movement relatively to the cam shaft.

60 The distributer is closed by a cap 80, having an axial hub 81, through which the rod 76 passes, a packing box 82 being screwed to the hub so as to pack the said rod. The pipe 31 leading from the sight feed cup, also 65 enters the hub 81.

A branch pipe 83 connects with the pipe 31 near its connection with the distributer, and this branch pipe is provided at its upper end with an ordinary valve-controlled oil cup 84, by means of which lubricating oil 70 may be conveyed to the distributer, and by turning compressed air into the distributer, this oil is driven into the engines, and a quick and convenient manner of lubricating them is thereby provided. 75

The operation of the starter is as follows: Assuming that the distributer is raised by the engagement of the rollers 72 with the cam tracks 71, and that the disks 51 and 55 are consequently out of engagement with 80 each other, the attendant first gives the timer a partial rotation, by means of a suitable lever 85, which moves the rollers 72 from under the cam portions of the tracks and allows the distributer to descend. The longer 85 pin 53 of the disk 51 then contacts with the face of the disk 55, and by turning the disk 51 in a reverse direction, the pin 53 enters the recess 54 of the disk 55, and is engaged by the opposite end of the recess as the 90 shorter pin 52 drops into the said recess. The cam 43 is now locked to the timer shaft, and the knob 77 indicates the engine that is ready to be fired, while the cam 43 is in engagement with the valve which opens the 95 pipe leading to the said engine. The valve 36 is then opened to admit a charge of explosive mixture to the sight feed cup 23, and the rod 38 of the valve 37 is depressed, permitting air under pressure to pass from the 100 tank 18 through the pipe 22 to the sight feed cup, expelling the explosive mixture therein out through the pipe 31 to the distributer; and assuming that the engines are fired in successive order, and that the piston of the 105 engine D is on the firing stroke, the cam 43 has engaged the valve 40, and opened communication with the said engine D, through the pipe 49, and the charge of explosive mixture is driven through the said pipe to 110 the said engine. The air raises the pressure in this engine and may force its piston down, but before the exhaust takes place the cam passes to the next valve 40, which opens communication with the engine C, whose 115 piston has moved toward the firing point, and the air enters the said engine C, driving its piston down, and thereby raising the piston of the engine D to the firing point, at which instant the timer forms a circuit through the spark plug of said engine and the batteries, causing an explosion which drives said piston down and brings the piston of the next succeeding engine C to the 120 firing point, thus starting the engines. After 125 the engines have gained sufficient speed, the spark current may be switched into the magneto, as will be understood, where the machine is supplied with one, and the timer is turned to advance the spark, thereby lifting 130

the distributor, which disconnects the clutch disks 51 and 55, and puts the distributor and cam 48 out of operation. Under proper conditions, however, the engine D may be fired 5 the instant the explosive mixture enters it.

Having described the invention, what I claim as new and desire to secure by Letters Patent, is:

1. In a starter for gasoline engines as specified, the combination with the engines of an explosive mixture distributor, having outlets corresponding to the number of engines and pipes connecting said outlets and engines; valves for normally closing said 10 outlets; a rotary cam for successively engaging said valves to open communication between the distributor and engines; a sight feed cup; a pipe connecting said cup with a supply of explosive mixture; a valve in said 15 pipe for determining the quantity of the mixture admitted to the cup; a pipe connecting the cup with the distributor; and means for delivering air under pressure to said cup, whereby the mixture is forced into the distributor and through the open valve to an 20 engine.

2. In a starter for gasoline engines as specified, the combination with the engines and the cam shaft, of an explosive mixture distributor, having outlet nipples corresponding to the number of engines and pipes connecting said nipples with the engines; valves for normally closing the inner ends of 30 said nipples; a rotary cam for successively operating said valves; means connected with the cam shaft for operating said rotary cam; and means for delivering charges of explosive mixture under pressure to said distributor.

3. In a starter for gasoline engines as specified, the combination with the engines and the cam shaft, of a distributor having equidistant outlets corresponding to the 45 number of engines; spring-pressed valves in the distributor which normally close said outlets; a rotary cam for successively engaging said valves to move them away from the outlets; and means connecting said cam with the cam shaft of the engines for operating said cam in unison with the said cam shaft; a sight feed cup; a valved pipe connecting said cup with a supply of explosive mixture; a pipe connecting said cup with the distributor; a pipe for connecting said cup 55 with a source of air under pressure; and means for normally closing connection between said cup and said air source.

4. In a starter for gasoline engines as specified, the combination with the engines, the cam shaft, and a timer geared to rotate in unison with said cam shaft, of a distributor having outlets corresponding to the number of engines; valves which normally close the outlets, and pipes connecting the 65 outlets with the engine; a rotary cam for

successively lifting said valves; a clutch mechanism for connecting said cam with the shaft of said timer; means connected with the timer for disconnecting said clutch mechanism; and means for delivering a charge of explosive mixture under pressure to said distributor.

5. In a starter for gasoline engines as specified, the combination with the engines, the cam shaft, a timer, the shaft of which is 70 geared to said cam shaft so as to rotate in unison therewith, and supported upon said timer, of a distributor above said timer; oppositely disposed cam tracks on the bottom of the distributor, which rest upon said rollers; pipes connecting said distributor with the engines; valves in the distributor for normally closing the outlets to said pipes; a rotary cam for opening the valves successively; a hollow stem on said cam which extends through the bottom of the distributor, and receives the upper end of the timer shaft; a clutch, one member of which is secured to the said stem, while the other member is secured to the timer shaft, said clutch 85 members being disconnected by the engagement of the rollers with the cam tracks when the timer is partially rotated; and means for delivering charges of an explosive mixture under pressure to said distributor.

6. In a starter for gasoline engines as specified, the combination with the engines and the cam shaft of a distributor, pipes connecting the same with the engines; valves for normally closing the pipes; a rotary cam for opening said valves successively; means connected with the cam shaft for rotating said cam in unison with the said cam shaft; a sight feed cup; a valved pipe connecting said cup with a supply of explosive mixture; a pipe connecting said cup with the distributor; a valved pipe connecting said cup with a source of air under pressure; a clutch connection between the rotary cam and the rotating means therefor; and means 100 for disconnecting the clutch.

7. In a starter for gasoline engines as specified, the combination with the engines and the cam shaft, of a shaft geared to said cam shaft to rotate in unison therewith; a timer on said shaft in circuit with the sparking devices of said engines, and a source of electrical power; a distributor; pipes connecting the same with the engines; valves which normally close said pipes; a rotary cam for successively opening said valves at a predetermined time relatively to the forming of a circuit by said timer; a clutch connection between said cam and said timer shaft; means for disconnecting the clutch, comprising rollers on the timer casing, and cam tracks on the distributor, said rollers being adapted to engage the cam tracks and lift the distributor when the timer is given a partial rotation; and means for delivering 115 120 125 130

charges of explosive mixture under pressure to said distributor

8. In a starter for gasoline engines as specified, the combination with the engines and the cam shaft, of an explosive mixture distributor, comprising a receptacle having outlets corresponding to the number of engines; spring pressed, pivotally mounted valves in the distributor, which normally close the outlets; pipes connecting the outlets with the engines; a rotary cam for opening said valves successively; means connected with the cam shaft of the engine for rotating said cam in unison with the said cam shaft; a sight feed cup; a valved pipe connecting said cup with a supply of explosive mixture; a pipe connecting said cup with the distributor; a pipe connecting the cup with a source of air under pressure; a valve in said pipe; and means for disconnecting the cam from its operating means.

9. In a starter for gasoline engines as specified, the combination with the engines and the cam shaft, of a distributor; pipes connecting the distributor with the engines; a sight feed cup; a valved pipe connecting the cup with a supply of explosive mixture; a pipe connecting the cup with the distributor; a valved pipe connecting the cup with a source of air under pressure; valves for controlling the outlets from the distributor; and means connected with the said cam shaft for operating said valves.

10. In a starter for gasoline engines as specified, the combination with the engines and cam shaft, of a distributor connected by pipes with the engines; valves in said distributor; a cam for operating the valves, a timer in circuit with the sparking system of said engines; gears connecting the timer with the cam shaft to cause the timer to rotate in unison with the cam shaft; a disk on the timer shaft having a circumferential recess; a disk connected to the cam having pins adapted to lie in said recess to lock the disks in engagement; means connected with the timer for raising the distributor to dis-

engage the disks; and means for delivering explosive mixture under pressure to the distributor.

11. In a starter for gasoline engines as specified, the combination with the engines, a cam shaft; a timer in circuit with the sparking system of said engines, gears connecting the timer with the cam shaft to cause the timer to rotate in unison with the cam shaft; and a distributor connected with the engines, having valves for controlling the outlets of said distributor; of a cam for operating said valves, having a stem extending through the bottom of the distributor; a disk on said stem having two depending pins of unequal length; a disk on the timer shaft having a circumferential recess adapted to receive the pins to lock the disks in engagement; means for uncoupling the disks; a sight feed cup connected with a supply of explosive mixture and with a source of air under pressure; and a pipe connecting said feed cup with the distributor.

12. In a starter for gasoline engines as specified, the combination with a distributor having outlets, valves for controlling the outlets, and a cam for operating said valves, of a sight feed cup, comprising a transparent receptacle having top and bottom caps; a tube secured to the top cap and extending through the bottom cap, having an aperture near its upper end; a pipe connecting said tube with the distributor; a second tube connected to the top cap and surrounding the first tube, said second tube extending to within a short distance of the bottom cap, an intervening space being left between said tubes; a pipe connecting the feed cup with a source of explosive mixture; and a pipe connecting said cup with a source of air under pressure.

In testimony whereof I affix my signature in presence of two witnesses.

HARRY MASON.
